Oscar Willis
Gitter Patent

The Blakeville referee is in this letter Agent and making part
of the same containing a description in the name of the late Oscar Willis
himself of his improvement upon the Railway Circular Riddle previously
patented by him now called the swinging Riddle.

To all to whom these presents shall come:

Be it known that I Oscar Willis of the County of Bunker's State of North
Carolina have invented a very useful improvement in the Railway Circular
Gitter Riddle which he calls the swinging Riddle, that the following is a
full & exact description of the construction & operation of said machine as
invented by me:

The frame is made of timber of any convenient size 4 feet 6
inches long 3 feet 6 inches wide with four posts 6 feet high, upon the frame
lengthwise rests two plates 6 feet 6 inches long, projecting one foot over the
posts. C. C. represent two angles 3 feet 6 inches long connected by three cross
pieces 3 feet long which form a frame upon which the middle rests.
Four chains are attached to the angles C. C. & suspended to the ends of the
plates, 3 plates the middle from the top, the others, b. represents a middle
made of plank, three feet six inches long two feet wide & eight inches deep
with an inclination of each end of forty five degrees, lined bottom
with sheet iron, perforated with holes, one end of the middle turns upon one
of the angles by means of hinges, while the other end may be raised with the
hinge. D. D. represents the Gaffers under the middle two & inches from
the bottom of the frame & filling it with an aperture at its bottom 8 inches
square. The frame side pieces extending up the end of the middle to prevent
it from falling sideways. The riddle is represented by E. is placed
with its end under the aperture of the Gaffers with an inclination great
or as high as circumstances may require, 30 inches wide ten feet long
by 16 inches deep with the riddle three inches long and eight inches apart.
The machine operates in the following manner: The gaffs expand

is thrown from a table or platform by a wheelbarrow, into the middle, above a plane of that end of the middle, detached from the top or frame and by swinging it backward and forward, give a peculiar action to the gravel. This is generally caused by a wheelbarrow tipping it in the usual manner. The gravel when thrown or thrown out of the middle, by elevating that end of the board or platform with the angle or end of frame into a wheelbarrow. My claim in this invention is entire with the exception of the rattle. The improvement for which I am desirous of obtaining a Patent is the suspending the middle upon bars at right angles to the inclined plane upon which the wheels of my Rattle may run. Detaching and suspending and give it a similar action.
